UNITED STATES PATENT OFFICE.

GEORGE E. ADAMS, OF PROVIDENCE, RHODE ISLAND.

DESIGN FOR A BUCKLE.

SPECIFICATION forming part of Design No. 21,363, dated February 23, 1892.

Application filed January 21, 1892. Serial No. 418,855. Term of patent 7 years.

To all whom it may concern:

Be it known that I, GEORGE E. ADAMS, of Providence, in the county of Providence and State of Rhode Island, have invented and produced a new and original Design for Buckles, of which the following is a specification, reference being had to the accompanying drawing, forming part thereof.

The drawing is a front view of a buckle 10 representing my new design.

The leading features of my design for buckles consist in the symmetrical outlines of the buckle-plate and the bar from which this plate depends.

15 2 in the drawing indicates a surface representing a bar from which the buckle-plate proper depends. From the lower edges of this surface 2 the outline of the buckle-plate extends in outward downward curves 3 3, then 20 inward and outward in generally contracting directions to 4 4, from where it curves inward and slightly upward to 5 5. The outlines now curve slightly inward and downward to 6 6, and then extend upward and approach each 25 other at 7 7, from whence they curve upward and slightly outward to meet the rectangular

clasp-ornament 8, the upper edge of which is connected with the curved portions 3 3 by wave-like lines in the surface of the plate.

The inner edges extend in directions to 30 represent, with the outlines above described, two large loops, the greatest diameter of which is at 3 3, and two smaller loops, the lower ends of which form the contracted portion of the buckle-plate, these loops being 35 held together in the center by the rectangular clasp ornament 8.

The surface ornamentation consists, mainly, of shading lines to accentuate the representation of loops of textile material in graceful 40 positions, the outlines of the larger loops being also indicated as crossing the surfaces of the smaller loops.

What I claim is--

The design for buckles, as herein shown 45 and described.

In witness whereof I have hereunto set my hand.

GEORGE E. ADAMS.
